(57) **CLAIM**

I claim the ornamental design for a cosmetic brush having a fan-like shape, as shown and described.

DESCRIPTION

FIG. 1 is a perspective view of a cosmetic brush having a fan-like shape.

FIG. 2 is a front elevation view thereof.

FIG. 3 is a rear elevation view thereof.

FIG. 4 is a bottom plan view thereof.

FIG. 5 is a top plan view thereof.

FIG. 6 is a left-side elevation view thereof; and,

FIG. 7 is a right-side elevation view thereof.

The broken lines illustrate features that form no part of the claimed design.

1 Claim, 3 Drawing Sheets
